UNITED STATES PATENT OFFICE.

BENJAMIN F. MCGUINNESS, OF WORCESTER, MASSACHUSETTS, ASSIGNOR TO CROMPTON & KNOWLES LOOM WORKS, A CORPORATION OF MASSACHUSETTS.

FILLING-THREAD-CUTTING DEVICE FOR WEFT-REPLENISHING LOOMS.

939,433.

Specification of Letters Patent.

Patented Nov. 9, 1909.

Application filed April 11, 1907. Serial No. 367,473.

To all whom it may concern:

Be it known that I, BENJAMIN F. MCGUINNESS, a citizen of the United States, residing at Worcester, in the county of 5 Worcester and State of Massachusetts, have invented certain new and useful Improvements in Filling-Thread-Cutting Devices for Weft-Replenishing Looms, of which the following is a specification.

10 My invention relates to a filling thread cutting mechanism for weft replenishing looms, and particularly to that class of looms having a magazine or reservoir for filled bobbins, and transferring mechanism 15 to transfer a filled bobbin from the magazine into a shuttle, on the practical or substantial exhaustion of the filling on the bobbin in the shuttle; said thread cutting mechanism being adapted to cut the filling 20 thread on the substantially exhausted bobbin, which is to be removed from the shuttle.

The object of my invention is to provide an improved filling thread cutting mechanism, adapted to be applied to and used on 25 looms of the class referred to, of any usual and well known construction.

In my improvements, I preferably provide a cutting mechanism having jaws to catch and hold the filling thread leading 30 from the goods being woven to the practically exhausted bobbin, near the edge of the goods, and also cutting blades to cut the thread contiguous to the holding jaws.

The holding jaws and cutting blades of 35 my cutting mechanism are normally closed, and are positively opened to receive the filling thread, and are yieldingly closed by a spring to hold and cut the filling thread. My improved filling thread cutting mechanism also acts to prevent the operation of 40 the transferring mechanism, in case the shuttle is not properly boxed on the magazine end of the loom.

In my improvements, as described herein, 45 I combine my filling thread cutting mechanism with the transerrer mechanism, so that when the bunter of the transerrer mechanism is raised into a position to be engaged by the dagger on the lay, the cutting mechanism, through connections to the bunter mechanism, is moved toward the selvage of the goods and into operative position, and as the lay moves forward toward the front 50 of the loom, a roll or other suitable device

carried on the lay, engages and positively 55 opens the holding jaws and the cutting blades, and allows the filling thread to pass between them, and the closing of said jaws and blades by a spring, as the roll is disengaged therefrom, on the continued forward 60 movement of the lay, will hold said thread and also cut it at the same time, and before the bobbin is discharged from the shuttle.

The engagement of the dagger on the lay, with the bunter of the transerrer mechanism, to operate the transerrer mechanism and transfer a bobbin from the magazine into a shuttle, will move my filling thread cutting mechanism to its inoperative position, all as will be hereinafter fully described.

I have only shown in the drawings a detached portion of a weft replenishing loom of the class referred to, with my improvements in filling thread cutting mechanism 75 applied thereto, sufficient to enable those skilled in the art to understand the construction and operation thereof.

Referring to the drawings:—Figure 1 is an inner side view of a detached portion of 80 a magazine stand or support, and the bunter of the transerrer mechanism, and my improvements in filling thread cutting mechanism combined therewith, and a sectional view of the lay beam with a shuttle thereon. 85 Fig. 2 corresponds to Fig. 1, but shows the cutting mechanism in its operative position, preparatory to holding and cutting the filling thread; the bunter, and other parts shown in Fig. 1 are not shown in this figure. 90 Fig. 3 shows the holding jaws and cutting blades in their closed position. Fig. 4 shows, on an enlarged scale, the cutting mechanism shown in Fig. 2, looking in the direction of arrow *a*, Fig. 5; the broken lines indicate 95 the inoperative position of the lever carrying said mechanism. Fig. 5 is an edge view of the cutting mechanism shown in Fig. 4, looking in the direction of arrow *b*, same figure. Fig. 6 shows the opposite side of 100 the cutting mechanism shown in Fig. 4, and looking in the direction of arrow *c*, Fig. 5. Fig. 7 is a plan view of the upper part of Fig. 5, looking in the direction of arrow *d*, same figure, showing a different position 105 of the lever hub.

In the accompanying drawings, 1 is the lower detached portion of the stationary

stand for the rotary magazine, not shown, which stand is secured to the loom side, not shown, in the usual way.

2 is the lower arm of the transerrer arm, 5 not shown, which has its hub 2' loosely mounted on a bolt 3 secured in a stand 4, bolted on the upper side of the breast beam, not shown, at the end thereof, in the usual way. The arm 2 has supported on its lower 10 end, in the usual way, a bunter 5, which, through the operation of the filling detecting mechanism, not shown, on the practical or substantial exhaustion of filling in the active shuttle, is operated, and raised into 15 the path of the dagger 6 on the front of the lay beam 7, in the usual and well known way, so that on the forward movement of the lay, the engagement of the dagger 6 with the bunter 5 will cause the movement of the 20 transerrer arm, to transfer a bobbin from the magazine into the shuttle, in the usual and well known way. On the lay beam 7 is 25 a shuttle box 8 for the shuttle 9.

All of the above mentioned parts may be 30 of the usual construction in the class of looms referred to.

I will now describe my improvements in 35 filling thread cutting mechanism combined with the parts above mentioned.

30 The stud 3 has loosely mounted thereon the hub 10' of a lever 10, which has a rearwardly and downwardly extending arm 10'' thereon, the lower end of which, in this instance carries a bolt 11, which is adjustable 35 in an elongated slot or opening 12' in a plate 12. The plate 12 is pivotally attached at its lower end by a pin 13 to the lower end of a second plate 14. The upper end of the plate 14 is yieldingly connected by a helically coiled contraction spring 15 to the upper end of the plate 12. Between the plates 12 and 14 extends the knob or projection 5' on the bunter 5, see Fig. 1 and said plates 12 and 14 form a yielding connection be- 40 tween the bunter 5 and the lever 10. The upper end of the lever 10 has, in this instance an elongated slot 10''' therein, through which extends a bolt 16' adjustably secured therein, which is pivotally connect- 45 ed to a rod head 16' on one end of a rod or connector 16. The other end of the rod or connector 16 has a rod head 16'' thereon, which is pivotally connected, through a pin 17, with the upper end of a centrally piv- 50 oted lever 18, see Fig. 1.

The lever 18 has a hub 18', see Fig. 5, which is loosely mounted on a stud 19 secured in the stationary stand 1. The hub 18' has in this instance a V shaped recess 18'' on 55 its inner end, see Fig. 7, which is adapted to receive a corresponding V shaped extension 20' on a collar 20, secured on the stud 19 by a set screw 21. A helically coiled tension and expansion spring 22 is secured at one end to 60 a collar 23 fast on the end of the stud 19, and

at its other end to the hub 18' of the lever 18. The spring 22 acts to yieldingly hold the hub 18' in engagement with the collar 20, and to return the lever 18 carrying the cutting mechanism, to its normal position, with the cutting mechanism in its inoperative position, after said lever has been moved by the raising of the bunter. The movement of the lever 18, through the hub 18' engaging the collar 20, will move the hub 18' and lever 18 70 to the left, as shown in Fig. 7, and also the cutting mechanism, and thus reduce the distance of the cutting mechanism from the selvage of the goods, when the cutting mechanism is in its operative position, so that 75 there will be no unnecessary strain on the filling thread leading from the goods, when it is held and cut, as the lay beats up.

I will now describe my holding and cutting mechanism.

85 On the lower end of the lever 18 is secured, in this instance by a bolt 24, the upper end of a plate 25, which preferably has an offset 25' therein, as shown in Fig. 5. The lower end of the plate 25 has a stud or screw 26' therein, on which is loosely mounted the lower holding or clamping jaw 26. The upper holding or clamping jaw 27, see Fig. 4, is riveted or otherwise attached to the front side of the plate 25, above the lower 90 clamping jaw 26. Both clamping jaws 26 and 27 are preferably made of fiber, or other suitable material, having engaging surfaces 26'' and 27' thereon, to hold the thread when it enters between said clamping jaws, as 95 shown in Fig. 2.

A spirally coiled contraction spring 28, attached at one end by a screw 29 to the plate 25, and at its other end to one end of the lower jaw 26, acts to move said jaw 26 toward the stationary jaw 27, as shown in 100 Figs. 1 and 3. The lower clamping jaw 26 has two screws 30 thereon, which extend into angular or cam shaped slots 31' in a slide or plate 31, and attach said slide to said lower 105 clamping jaw 26. The lower edge of the slide or plate 31 extends into the path of and is adapted to be engaged by a roll 32, mounted and adapted to rotate on a stand or arm 33 secured to the front side of the lay beam 110 7, see Fig. 2.

115 On the opposite side of the supporting plate 25, from the clamping jaws 26 and 27, are located the two cutting blades 34 and 35, see Fig. 6. The upper cutting blade 34 is in this instance riveted or otherwise rigidly secured to the plate 25. The lower blade 35 has a hub 35', see Fig. 5, which is loosely mounted on a screw or stud 36, secured to the plate 25. A helically coiled expansion spring 120 37 encircles the bolt 36, and bears at one end against the head thereof, and at the other end against the outer end of the hub 35', and acts to yieldingly move inwardly the lower cutting blade 35, and hold it in proper posi- 125 130

tion relatively to the cutting blade 34. To the lower cutting blade 35, on the opposite side of its pivotal support from its cutting edge, is secured a plate 38 having an angular or cam shaped slot 38' therein, into which extends a pin 39 on the lower clamping jaw 26. The movement of the lower clamping jaw 26, through the engagement of the pin 39 thereon with the slot 38' in the plate 38, causes the movement of the lower cutting blade 35, and moves it toward the upper cutting blade 34, to cut or sever the filling thread, and also moves it away from said upper cutting blade.

15 From the above description in connection with the drawings the operation of my improvements will be readily understood by those skilled in the art.

In the normal operation of the loom, the cutting mechanism will be in its inoperative position, as shown in Fig. 1, but when the bunter 5 is raised, through the operation of the filling detecting mechanism, to be in a position to be engaged by the dagger 6, 20 then through the plates 14 and 12, and arm 10" on the lever 10, and rod or connector 16 to the lever 18, said lever 18, and the clamping and cutting mechanism carried thereon, is moved into its operative position, 25 as shown in Fig. 2. As the lay moves forward, the engagement of the roll 32 on the stand 33 with the lower edge of the slide or plate 31, see Fig. 2, will cause said plate and the outer end of the lower clamping 30 jaw 26 to move upwardly, against the action of the spring 28, and move downwardly the inner clamping end of said jaw, and with it in the lower cutting blade 35, to leave an opening between the clamping jaws 26 and 35 35 and the cutting blades 34 and 35, for the entrance of the filling thread as the lay moves forward, as shown in Fig. 2. When on the continued forward movement of the lay, the roll 32 passes off of the lower edge 40 of the plate or slide 31, the spring 28 is free to act to move upwardly the clamping edge of the lower clamping jaw 26, to clamp the thread between the lower and upper clamping jaws. The lower cutting blade 35 moves 45 upwardly with the lower clamping jaw 26, and cuts the thread extending between the clamping jaws and the cutting blades. On the return backward movement of the lay, the roll 32 passes under the plate or 50 slide 31, and raises said blade on the screws or studs 30, as shown in Fig. 3, without moving the lower clamping jaw 26. The return of the bunter 5 to its forward lowered position, in the usual way, will, through 55 intermediate connections to the cutting mechanism, move the cutting mechanism to its normal inoperative position shown in 60 Fig. 1.

In case, for any reason, the shuttle is not 65 properly boxed, and extends beyond the in-

ner end of the shuttle box, and through the operation of the filling detecting mechanism the bunter is raised into its operative position, and consequently the cutting mechanism is moved into its operative position, 70 the projecting end of the shuttle, as the lay moves forward, will strike against the thread cutting mechanism, a smash will be prevented by the backward movement of the cutting mechanism, and through the 75 give-way or yielding connection of the arm 10" on the lever 10, with the bunter 5, the bunter 5 will be moved into its lowered inoperative position.

By reason of the hub 18' of the lever 18 of the cutting mechanism, having the V shaped recess therein, into which extends the V shaped extension on the collar 20 fast on the stationary stud 19, the rotation of the hub 18' on the stud 19, when the cutting 85 mechanism is moved into its operative position, will cause the hub 18' and the lever 18 to move inwardly and carry the cutting mechanism toward the goods being woven, so that as the lay beats up, and the filling 90 thread passes between the holding jaws and the cutting blades, and the thread is held and cut, there will be no undue strain on the thread during the cutting operation, which would occur if the cutting mechanism remained in the same position relative to the selvage of the goods, as the lay beats up.

It will be understood that the details of construction of my improvements may be 100 varied if desired.

Having thus described my invention, what I claim as new and desire to secure by Letters Patent is:—

1. In a weft replenishing loom, a filling 105 thread cutting mechanism supported independently of the lay, and connected with the filling transfferer mechanism, and moved inwardly toward the selvage of the goods into operative position, preparatory to the transfer of filling, and subsequently moved outwardly and away from the selvage of the goods, and means for moving said filling thread cutting mechanism inwardly and outwardly.

2. In a weft replenishing loom, a filling 110 thread cutting mechanism supported independently of the lay, and connected with the filling transfferer mechanism, and moved inwardly toward the selvage of the goods, into operative position, preparatory to the transfer of filling, and subsequently moved outwardly and away from the selvage of the goods, and into position to be engaged by a shuttle not properly boxed, and means for moving said filling thread cutting mechanism inwardly and outwardly.

3. In a weft replenishing loom, a filling 115 thread cutting mechanism supported independently of the lay, and connected with the 120

115

120

125

130

filling transferrer mechanism, and moved inwardly toward the selvage of the goods, into operative position, preparatory to the transfer of filling, and subsequently moved 5 outwardly and away from the selvage of the goods and into position to be engaged by the shuttle not properly boxed, and means for moving said filling thread cutting mechanism inwardly and outwardly, said filling 10 thread cutting mechanism comprising two holding or clamping jaws, and two cutting blades, normally yieldingly held in closed position, and means for yieldingly holding said jaws in closed position, and 15 positively opened to receive the filling thread on the forward beat of the lay, and means for positively opening said jaws.

4. In a weft replenishing loom, a filling thread cutting mechanism, comprising two 20 holding or clamping jaws, and two cutting blades, normally yieldingly held in closed position, and adapted to be positively opened to receive the filling thread, by engagement with a roll or device carried on the lay, on 25 the forward beat of the lay, and yieldingly closed on disengagement from said roll or device, said clamping jaws and cutting blades being supported on a plate attached to a lever, and said plate and lever, said 30 lever pivotally mounted on a stationary stud, and its hub adapted to be rotated and moved longitudinally on said stud, and a spring connected with said hub, and connections intermediate said lever and the bunter of the 35 transferrer mechanism, and said bunter, the movement of which into its raised position will move the cutting mechanism into its op-

erative position, and the movement of which, to operate the transferrer arm through the engagement of the dagger on the lay, will 40 move said cutting mechanism into its inoperative position.

5. In a weft replenishing loom, a filling thread cutting mechanism, comprising two holding or clamping jaws, and two cutting 45 blades, normally yieldingly held in closed position, and adapted to be positively opened to receive the filling thread, by engagement with a roll or device carried on the lay, on the forward beat of the lay, and yieldingly 50 closed on disengagement from said roll or device, said clamping jaws and cutting blades being supported on a plate attached to a lever, and said plate and lever, said lever pivotally mounted on a stationary stud, 55 and its hub adapted to be rotated and moved longitudinally on said stud, and a spring connected with said hub, and connections intermediate said lever and the bunter of the transferrer mechanism, and said bunter, the 60 movement of which into its raised position will move the cutting mechanism into its operative position, and the movement of which, to operate the transferrer arm through the engagement of the dagger on 65 the lay, will move said cutting mechanism into its inoperative position, and a yielding connection between said bunter and the connections to the cutting mechanism.
